The ornamental design for a vehicle fog lamp, as shown and described.

DESCRIPTION

FIG. 1 is a perspective view of a left vehicle fog lamp;

FIG. 2 is another perspective view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The novel design also includes an embodiment of a right side vehicle fog lamp which is mirror symmetrical to the embodiment of FIGS. 1-7 and therefore is not separately illustrated.
